(57) **CLAIM**

The ornamental design for a compact mirror, as shown and described.

DESCRIPTION

FIG. 1 is a perspective view of the compact mirror showing my new design.

FIG. 2 is a top view thereof.

FIG. 3 is a bottom view thereof.

FIG. 4 is a front view thereof;

FIG. 5 is a rear view thereof;

FIG. 6 is a right side view thereof;

FIG. 7 is a left side view thereof; and,

FIG. 8 is another perspective view thereof in an open configuration.

The broken lines in the drawings illustrate portions of the compact mirror which form no part of the claimed design.

1 Claim, 8 Drawing Sheets
